UNITED STATES PATENT OFFICE.

JOHN G. VON HOFE, OF NEW YORK, N. Y.

WALL CONSTRUCTION.

No. 831,345.

Specification of Letters Patent.

Patented Sept. 18, 1906.

Application filed May 20, 1905. Serial No. 261,340.

To all whom it may concern:

Be it known that I, JOHN G. VON HOFE, a citizen of the United States, and a resident of the city of New York, borough of Manhattan, in the county and State of New York, have invented a new and Improved Wall Construction, of which the following is a full, clear, and exact description.

My invention relates to a wall construction especially adapted for use with concrete veneered walls.

The principal object of the invention is to provide means whereby building-blocks can be readily and permanently attached to the surface of a wall formed of continuous masses of concrete or other plastic material.

Certain other objects are also involved, and they will appear below.

Reference is to be had to the accompanying drawings, forming a part of this specification, in which similar characters of reference indicate corresponding parts in all the figures.

Figure 1 is a perspective view of a building-block, showing one form of my invention. Fig. 2 is a rear view of a portion of a wall constructed of these blocks. Fig. 3 is a sectional view on the line 3 3 of Fig. 2, showing the blocks slightly modified. Fig. 4 is a sectional view on the line 4 4 of Fig. 2. Fig. 5 is a perspective view of another form of block embodying the principle of my invention. Fig. 6 is a view similar to Fig. 2, showing the blocks illustrated in Fig. 5. Fig. 7 is a plan of a course of blocks of the second form, and Fig. 8 is a sectional view on the line 8 8 of Fig. 6.

My invention is designed especially to be employed with walls formed in place by molding concrete or other plastic material between a wall of veneering-blocks and a temporary backing. Such walls are preferably provided upon their front surfaces with blocks having a surface exposed on the front side that will be more or less ornamental or will resemble any other kind of building-wall. Any desired kind of veneering-blocks can be used for this purpose, and my invention applied thereto.

In its simplest form the invention comprises an undercut recess formed in each block, so that the plastic material of which the main body of the wall is composed will enter said recess and securely hold the blocks in position upon the wall. This provides for a most efficient bond between the main body

of the wall and the veneering-blocks and also allows the wall to be built and veneered with a minimum expenditure of labor. It will be understood that the blocks are placed on the front of the mold or molding-space before the plastic material is introduced and that the blocks are arranged in the way in which they are desired to appear in the finished wall.

The block shown in Fig. 1 may be of any desired form, but is provided on each end with a recess *a*, which is connected by a perforation *b* through the rear wall thereof with plastic material *c*, which constitutes the main body of the wall. It will be noticed that the cross-sectional area of the cavity or depression *a* is larger than the area of the opening or perforation *b*, and consequently a T-shaped lock will be provided by the plastic material entering this cavity at *c'*. In other words, the recess *a* is undercut. In the form illustrated in the first four figures the perforations *b* are semicircular, so that when two blocks are arranged end to end circular openings are provided; but it will be understood that any other desired shape may be employed.

In the form shown in Fig. 5 each corner of the block is provided with a recess *d*, and from these recesses extend undercut portions *e* toward the interior of the block or in any other desired direction. Each of the recesses *d* is in this form a quarter of a circle, and when the blocks are arranged as shown in Fig. 6 they form semicircles with each other. If, however, the blocks were arranged so as not to break joints, complete circles would be formed. In any event the plastic material of the wall *c* enters the recesses to form locks *c'* similar to the locks *c*.

In building the wall the veneering-blocks are set up in the position in which it is intended to have them remain in the finished wall, preferably breaking joints, as shown in Figs. 2 and 6. After a sufficient number of courses are placed in this position the concrete or other plastic material is poured in behind them, and it enters the recesses described, so as to form the locks *c'* and *c*. This locking operation is therefore accomplished in the most simple and efficient manner merely by the flow of the material by gravity, or if a dry-molding system is employed by the tamping of the mold material. The plastic material hardens in place and forms an absolutely perfect joint and lock to bind the ve-

neering-blocks to the main body of the wall, and it is believed that the best construction of veneered wall is thus produced. If desired, the main part of the wall may be provided with air-spaces by placing cores in it, and after one layer has hardened raising them, so that they serve for the entire wall. These air-spaces are preferably alternately arranged with the air-spaces of the blocks, so as to break joints with them, as shown in Fig. 3, in order that a particle of moisture in traversing the wall from any point will encounter an air-space.

Having thus described my invention, I claim as new and desire to secure by Letters Patent—

1. A wall having a body of plastic material, and a veneer of blocks each block having an undercut recess on its end for receiving a bond integral with the plastic material, the recesses being bounded on all sides by walls

of the blocks which abut against each other at their ends, the one of said walls adjacent to the plastic material being perforated to permit the admission of said bond.

2. A wall comprising a body of plastic material having vertical parallel passages therethrough, and a veneer of blocks having vertical parallel passages alternately arranged with respect to the first-named passages, the abutting ends of the said blocks being recessed, and perforated adjacent to the plastic material whereby to receive a bond integral with the plastic material.

In testimony whereof I have signed my name to this specification in the presence of two subscribing witnesses.

JOHN G. VON HOFÉ.
